(57) **CLAIM**

The ornamental design for a tethered pocket vest, as shown and described.

DESCRIPTION

FIG. 1 is a front plan view of my new design for a tethered pocket vest showing a tethered pocket for a radio and the like.

FIG. 2 is a top plan view of the tethered pocket vest shown in FIG. 1.

FIG. 3 is a right side plan view of the tethered pocket vest shown in FIG. 1.

FIG. 4 is a back plan view of the tethered pocket vest shown in FIG. 1.

FIG. 5 is a bottom plan view of the tethered pocket vest shown in FIG. 1.

FIG. 6 is a left side plan view of the tethered pocket vest shown in FIG. 1.

FIG. 7 is a front plan view of the tethered pocket vest shown in FIG. 1, with the tethered pocket secured to an upper pocket for transport use.

FIG. 8 is a back plan view of the embodiment shown in FIG. 7.

FIG. 9 is an inside out front plan view of the tethered pocket vest shown in FIG. 1.

FIG. 10 is a back plan view of the inside out view of FIG. 9.

FIG. 11 is a front perspective view of the FIG. 7 embodiment shown worn by a user; and,

FIG. 12 is a front perspective view of the FIG. 1 embodiment shown worn by a seated user.

The broken line showing of the person and headphones in FIG. 11 and FIG. 12 is for illustrative purposes only and forms no part of the claimed design.

In all figures, the broken lines on the surface of the tethered pocket vest represent stitching.
